Primary Examiner — Keith J Wilson(74) *Attorney, Agent, or Firm* — NorthStar Law Group; Thomas J. Bassolino(57) **CLAIM**

The ornamental design for an inflatable object, as shown and described.

DESCRIPTION

FIG. 1 is a top, front, right perspective view of an inflatable object, showing our new design;

FIG. 2 is a top, back, left perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line showing of environmental matter is for illustrative purposes only and forms no part of the claimed design.
